United States Patent Office.

A. ELY BEACH, OF STRATFORD, CONNECTICUT.

Letters Patent No. 70,504, dated November 5, 1867.

IMPROVEMENT IN PNEUMATIC RAILWAYS.

The Schedule referred to in these Letters Patent and making part of the same.

TO ALL WHOM IT MAY CONCERN:

Be it known that I, A. ELY BEACH, of Stratford, in the county of Fairfield, and State of Connecticut, have invented a new and useful Improvement in Pneumatic Railways; and I do hereby declare that the following is a full, clear, and exact description thereof, which will enable those skilled in the art to make and use the same, reference being had to the accompanying drawings, forming part of this specification.

Figure 1 is a perspective view of my improvements.

Figure 2 is a vertical sectional elevation thereof.

Figures 3 and 4 are perspective views illustrating modifications of my improved track-base.

Similar letters of reference indicate corresponding parts.

The object of these improvements is to facilitate the stoppage of the pneumatic cars at way-stations; also to provide an effective support for the rails within the pneumatic tube; also to facilitate the lighting of the pneumatic tube.

Referring to the drawings, A is the pneumatic tube, to be made of any of the known forms or materials. B is an opening in said tube, representing a way-station or landing-place for the cars; and B' is a sliding door for closing the opening. One or more doors may be employed. D represents the pneumatic car in position at a landing station. The car is to be driven through the tube by atmospheric pressure, and the motion of the car is to be arrested by brakes applied in the usual manner. In order to facilitate the stoppage of the car at the station, and at the same time permit the driving air-current to flow freely onward through the tube while the car is standing at the station, I enlarge the tube at and near the station, as indicated by C in figs. 1 and 2. Although the enlargement of the tube is intended to be sufficient to permit the passage of the air around one side of the car, there will necessarily be a reduced air pressure against the car while standing at the station, which pressure is overcome by the pressure of the brakes. To start the car, it will only be necessary to release the brakes, when the existing air pressure on the car will carry it slowly in the direction of the arrow to the line x x, where the tubular enlargement terminates, and where the full pressure of the driving air-current will be brought against the car. The enlargement here represented is lateral, but it will be readily understood that the tube may be enlarged vertically, or both vertically and laterally. The enlargement longitudinally will be carried beyond each end of the stopping place as far as may be required to insure the proper arrest of the car. To prevent the escape of the air at the station when the opening B is uncovered, the tube and track are so formed and arranged that the body of the car, when standing at the station, will extend across or cover the opening and prevent leakage of air. An additional or modified means of preventing the leakage of air through the opening B consists in using valves, F' F'', which pass through slots made in the tube, and are intended to be pushed inward, when the car is at the station, until the inner edges of the valves come in contact with the car body, the valves being made purposely to fit the car body. These valves are to be arranged on each side of the opening B, and when the valves are pushed in there can be no leakage between the car body and the valves. The valves are to be operated by means of handles f f'. For the purpose of firmly supporting the pneumatic cars and the rails on which they run, I provide the interior of the tube with a cradle, E, which fits within the tube, and corresponds to the form of the bottom thereof. The rails b rest upon the upper edges of the cradle, and may be secured thereto in any suitable manner. The rails may be made with lips, or in the form of angle-irons, and one edge of the rails may project over and down the edges of the cradle, forming a fastening to keep the ends of the bars composing the cradle always in place. It will be observed that the cradle forms an inverted arch which receives and supports the weight of the cars. The cradle may form a part of the tube, or may be made separate therefrom, and attached, if necessary, by any suitable fastening. As shown in fig. 3, the cradle is composed of a series of transverse curved bars, e e', laid side by side. A modification would consist in having the bars separated, as shown by e' e'', with blocks e''' between the bars. Another modification would consist in composing the cradle of a series of longitudinal bars, as shown in fig. 4; these bars being laid in contact with each other, or separated by means of blocks placed between the bars. g g are the wheels of the car. In order to effect the lighting of the interior of the tube, I make a recess, F, in the wall of the tube, the bottom of which is closed, forming a combustion-chamber in which the light is placed. To prevent the light from being extinguished by the strong currents of air which move through the tube, I

place a glass plate, G, in the lower part of the recess F, nearly flush with the interior of the tube. Small apertures in the plate G admit air to supply the flame of the light.

I do not limit or confine myself to the form or arrangement of any of the devices here shown and described, as they may be modified in various ways without departing from my invention.

What I claim as new, and desire to secure by Letters Patent, is—

1. The enlargement of the tube at and near the stopping station, substantially as and for the purpose herein shown and described.
2. The method of preventing the leakage of air at the openings, substantially as herein shown and described.
3. The method of supporting the cars and rails, substantially as herein shown and described.
4. The recess F for lighting the tube, substantially as herein shown and described.

A. ELY BEACH.
